FILLMORE BUSHEY

UNITED STATES PATENT OFFICE.

FILLMORE BUSHEY, OF ST. ALBANS, VERMONT.

COUPLING.

1,131,820.

Specification of Letters Patent. Patented Mar. 16, 1915.

Application filed August 24, 1914. Serial No. 858,357.

To all whom it may concern:

Be it known that I, FILLMORE BUSHEY, a citizen of the United States, residing at St. Albans, in the county of Franklin and State 5 of Vermont, have invented certain new and useful Improvements in Couplers, of which the following is a specification, reference being had to the accompanying drawings.

This invention relates to certain improvements in couplers and has relation more particularly to a device of this general character especially designed and adapted for use in connection with train lines, and an object of the invention is to provide a device of this 15 general character having novel and improved means whereby the coupling of the train lines is effected in substantially an automatic manner.

It is also an object of the invention to provide a coupler of this general character whereby the lines may be automatically closed upon the separation of the coupler.

Furthermore, it is an object of the invention to provide a device of this general character having novel and improved means capable of manual operation whereby the line for the brakes may be maintained open upon the separation of the coupler.

The invention consists in the details of 30 construction and in the combination and arrangement of the several parts of my improved coupler whereby certain important advantages are attained and the device is rendered simpler, less expensive and otherwise more convenient and advantageous for use, all as will be hereinafter more fully set forth.

The novel features of the invention will be carefully defined in the appended claims.

40 In order that my invention may be the better understood, I will now proceed to describe the same with reference to the accompanying drawings, wherein—

Figure 1 is a side elevational view of a 45 coupler constructed in accordance with an embodiment of my invention; Fig. 2 is a bottom plan view of the device as disclosed in Fig. 1, with a part thereof in section; Fig. 3 is a fragmentary view in top plan, on a reduced scale, of my improved coupler as 50 herein embodied; Fig. 4 is a sectional view taken substantially on the line 4—4 of Fig. 1; Fig. 5 is a front elevational view of one 55 of the heads comprised in my improved coupler; Fig. 6 is an enlarged sectional view, detached, taken longitudinally of the con-

trolling valve herein disclosed as interposed in the air line; and Fig. 7 is a sectional view taken substantially on the line 7—7 of Fig. 6.

As disclosed in the accompanying drawings, D denotes a draw bar of conventional construction suitably supported by the end of a car C and depending from the forward end of the draw bar D is a yoke 1 directed through the elongated longitudinally disposed slot 2 produced in the tail 3 of a coupler head 4. The free extremity of the tail 3 of the head is reduced, as indicated at 5, and is preferably circular in cross section 70 and is disposed through a suitable opening 6 produced in the plate 7 depending from the draw bar D and surrounding the reduced portion 5 is the expansible member 8, herein disclosed as a coil spring, and interposed between the plate 7 and the shoulder 9, afforded by such reduced extremity. By this arrangement, it will be readily perceived that the head 4 is effectively supported in a manner as to be entirely free of strain incident to the car motion and which is capable of operative engagement with a coacting head with a minimum of shock and in order that the coupler may have the requisite flexibility, I find it in practice of advantage to 85 have the reduced extremity 5 formed of a separable piece and hingedly engaged with the tail 3 through the medium of the vertically disposed pivot pin 10, it being preferred that the free end of the tail be provided with a socket, as indicated at 11, to receive the adjacent extremity of the separable reduced portion 5.

The head 4 is substantially pyramidal in form and one longitudinal half thereof is 95 hollow to afford a pyramidal recess 12 adapted to receive the pyramidal extension 14 of the coacting head and it is to be observed that the contiguous faces of the recess 12 and the extension 14 are flush one with the other so that the coacting heads, when assembled, have a substantially wedge action, as is believed to be clearly apparent to those skilled in the art to which my present invention appertains.

As herein embodied, the head 4 at substantially the base of the extension 14 is provided with a plurality of superimposed transversely disposed ports 15, the uppermost port being adapted to coact with the air 110 line for the brake system, the intermediate port with the signal line, and the lowermost

port with the steam line, each of such ports having projecting laterally from the head, the nipples 16 with which the flexible hose 17 is connected, said hose leading to the respective lines 18 carried by the car. As is believed to be self-evident, when the coacting heads are assembled, the ports of one are adapted to register with the ports of the other so that the requisite flow may be permitted.

Disposed within the inner extremities of each of the ports 15 is a sleeve 19 having produced at its inner extremity a valve seat 20 with which is adapted to coact a valve 21 carried by the stem 22 disposed axially of the sleeve and having its forward extremity provided with a parti-spherical head 23 normally projecting beyond the inner face of the recess 12 and maintained in such normal position through the medium of the expansible member 24 herein disclosed as a coil spring interposed between the spider 25 and the annular flange 26 carried by the stem 22. By this arrangement, it will be observed that as the extensions 14 enter within the respective recesses or pockets 12 the valve 21 will be automatically forced into an open position, it being understood that the head 23 is suitably perforated in order to permit the requisite flow of the fluid therebeyond.

I have found in practice that it is essential to provide means whereby the valve for controlling the flow through the upper port 15, which is comprised in the air line for the brake system, be prevented from closing especially in case of a train breaking, and, as herein set forth, this is accomplished by having projected within the sleeve 19 of such port the vertically disposed shaft 27, the inner extremity whereof being provided with a laterally disposed cam member 28 adapted to engage the annular flange 26 carried by the stem 22 whereby it will be readily perceived that upon proper rotation of the shaft 27 the valve 22 will be forced into an open adjustment and in order to maintain such adjustment the upper or projected extremity of the shaft 27 is angularly disposed to afford a means whereby the shaft 50 may be manually operated and adapted to be engaged by the hook or latch member 29 carried by the coacting head 4.

The hook or latch member 29 is pivotally supported by the head 4 for movement in a vertical plane and any suitable means may be employed in connection therewith for adjusting the same into inoperative position in order that such port may be closed should the necessities of practice so require. As I do not wish to be understood as limiting myself to any particular means for adjusting the hook or latch member 29, I refer to the same as a whole by the reference character 30.

While not essential, I find it of advantage

to provide the opposed faces of the respective heads 4 with the gaskets 31 of suitable dimensions and preferably formed of hard rubber or the like, for reasons which are believed to be clearly apparent.

From the foregoing description, it is thought to be obvious that a coupler constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. A coupler of the character described comprising coacting complemental heads, each of said heads having ports disposed therethrough, the ports of one head being adapted to register with the ports of a second head when said heads are coupled, a line connection with each of the ports, valves for controlling the flow through the ports and normally projecting beyond the inner faces of the heads and adapted to be engaged by the coacting head, a shaft rotatably supported by each of the heads, a cam carried by the shaft and adapted to coact with one of the valves for maintaining the same in an open adjustment upon axial rotation of the shaft, and means for holding the shaft against axial rotation.

2. A coupler of the character described comprising coacting complemental heads, each of said heads having ports disposed therethrough, the ports of one head being adapted to register with the ports of a second head when said heads are coupled, a line connection with each of the ports, valves for controlling the flow through the ports and normally projecting beyond the inner faces of the heads and adapted to be engaged by the coacting head, a shaft rotatably supported by each of the heads, a cam carried by the shaft and adapted to coact with one of the valves for maintaining the same in an open adjustment upon axial rotation of the shaft, said shaft being provided with an angular portion to afford a means whereby the shaft may be axially rotated, and means coacting with the angular portion of the shaft for holding the same against axial rotation.

3. A coupler of the character described comprising coacting complemental heads, each of said heads having ports disposed therethrough, the ports of one head being adapted to register with the ports of a sec-

ond head when said heads are coupled, a line connection with each of the ports, valves for controlling the flow through the ports and normally projecting beyond the inner faces of the heads and adapted to be engaged by the coacting head, a shaft rotatably supported by each of the heads, a cam carried by the shaft and adapted to coact with one of the valves for maintaining the same in an open adjustment upon axial rotation of the shaft, said shaft being provided with an angular portion to afford a means whereby the shaft may be axially rotated, and means carried by one head coacting with the angular extremity of the shaft of the second head for holding said shaft against axial rotation.

4. A coupler of the character described comprising coacting complementary heads, each of said heads having ports disposed therethrough, the ports of one head being adapted to register with the ports of a second head when said heads are coupled, a

line connection with each of the ports, valves for controlling the flow through the ports 25 and normally projecting beyond the inner faces of the heads and adapted to be engaged by the coacting head, a shaft rotatably supported by each of the heads, a cam carried by the shaft and adapted to coact 30 with one of the valves for maintaining the same in an open adjustment upon axial rotation of the shaft, said shaft being provided with an angular portion to afford a means whereby the shaft may be axially 35 rotated, and a latch member carried by each of the heads coacting with the angular portion of the shaft of the adjacent head for holding said shaft against axial rotation.

In testimony whereof I hereunto affix my 40 signature in the presence of two witnesses.

FILLMORE BUSHEY.
